UNITED STATES PATENT OFFICE.

DUNCAN W. PATTERSON, OF CRANFORD, NEW JERSEY, ASSIGNOR TO MACANDREWS AND FORBES COMPANY, OF CAMDEN, NEW JERSEY, A CORPORATION OF NEW JERSEY.

FIRE-EXTINGUISHING SYSTEM OF THE SPRINKLER-HEAD TYPE.

1,259,903.

Specification of Letters Patent. Patented Mar. 19, 1918.

Application filed June 8, 1917. Serial No. 173,517.

To all whom it may concern:

Be it known that I, DUNCAN W. PATTERSON, a citizen of the United States, residing at Cranford, in the county of Union and 5 State of New Jersey, have invented new and useful Improvements in Fire-Extinguishing Systems of the Sprinkler-Head Type, of which the following is a specification.

This invention relates to improvements in 10 fire extinguishing systems, pertaining more particularly to the construction and arrangement of sprinkler-head units usable in such systems.

In installing fire extinguishing apparatus 15 in buildings, etc., where the extinguishing medium is brought directly into an overhead position in a room, it is the general practice to employ one or more sprinkler-head units which normally retain the conduit for the 20 medium closed against discharge of the medium, with the unit arranged in such manner that in the presence of higher temperatures, such for instance as are produced by fire conditions, the holding means for the 25 closure will be automatically released to permit discharge of the medium. By employing a plurality of units in a conduit header, a comparatively large amount of extinguishing medium can be delivered at the point 30 where the temperature conditions open up the conduit.

So far as I am aware, sprinkler-head systems have been confined entirely to apparatus where a single medium is used, being 35 either water or solution of some fire extinguishing salt in water, thus limiting this type of installation to the use of a particular form of extinguishing medium. While such 40 system—the sprinkler-head system—is particularly advantageous by reason of its being permanently located at the point where needed and ready for operation, it has the disadvantage of limiting the fire extinguishing operation to practically the use of water 45 or a single solution of water and a fire extinguishing salt in comparatively large amounts.

Developments in the fire extinguishing art made in recent years provide a more efficient 50 extinguishing medium by what is known as the foam-extinguishing process, this process employing individual solutions which, when brought together, produce a gas which is noxious to the fire flame, one or both of the 55 solutions carrying an ingredient which pro-

duces a foam effect when the solutions are commixed. Various ways of utilizing the foam-extinguishing process have been contemplated, but, so far as I am aware, the possibility of utilizing such process in connection with a sprinkler-head system, has not been contemplated, due probably to several difficulties which are inherent in connection with the use of the process. For instance, the solutions must normally be kept 60 separate, the product resulting from the commixture spending itself, thus decreasing the value of the commixed solutions. This practically prevents maintaining the headers filled with the commixed solutions ready 65 to be discharged. A somewhat similar effect is present where an attempt is made to provide the commixture of the solutions at a single point and then carry the commixed solutions through the lines to the open 70 sprinkler-head unit, since the travel of the commixed solution tends to reduce the efficiency.

The present invention is designed to meet 75 these and other objections and permit of the 80 use of the foam type of extinguishing medium in connection with sprinkler-head systems. This is made possible by maintaining the solutions separate within the conduit system, and commixing the solutions after 85 they have passed from the conduits. This result I obtain by the use of a sprinkler-head unit in which the several solutions are discharged in proximity to each other in a more or less stream-like manner, and obstructing 90 the flow path of the stream to force the component elements of the stream into a commixed relation, whereupon the chemical reactions immediately take place and the medium distribution is practically at its greatest efficiency owing to the fact that it is put 95 into service immediately upon its formation, the commixing taking place in the open air and under the most favorable conditions.

To these and other ends, therefore, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings,
Figure 1 shows a sprinkler-head unit mounted on a conduit header, with the solu- 110

tion discharge openings closed by the holding means for the closure.

Fig. 2 is a sectional view taken through a portion of a unit, showing one way in which 5 the discharge member may be formed.

Fig. 3 is a diagrammatic view showing the configuration of the solution discharge portion of the member.

Figs. 4 and 6 are views similar to Fig. 10 2 showing other forms of solution discharge elements.

Fig. 5 is a diagrammatic view showing the arrangement of the discharge openings of the structure of Fig. 4.

15 Fig. 7 is a sectional view taken on line 7-7 of Fig. 6.

In illustrating the invention, a single unit is shown, it being understood that each unit is connected to each of the solution lines, 20 the latter being independent of each other, so that when the system is inactive, and each of the units are closed, the several solutions will be maintained free from admixture. So far as the present invention is concerned, 25 the several solutions may be held within the pipe lines, or may be normally maintained out of such lines and brought into the lines when needed, as for instance is referred to in the patent to Walker, 1,186,249, June 30 6, 1916, or in my companion application filed March 13, 1917, Ser. No. 154,471.

While the solutions employed may be of any desired type, I prefer to employ what is known as the "foamite" solution, in which 35 one of the solutions is formed of aluminum sulfate and water, while the other solution is formed of sodium bi-carbonate, water and "foamite", these solutions, when commixed, producing the desired foam-extinguishing 40 medium.

The present invention comprises primarily a solution discharge element *a* having a closure *a'* and a yoke *a²* carrying a member *a³*, (which may be threaded or 45 otherwise secured to the yoke) the inner end of the member *a³* being opposite the exposed face of closure *a'*. *b* designates the holding means for the closure, this means extending between the inner end of member 50 *a³* and the closure *a'*, and being preferably formed of two members which are normally held in proper relative position by a suitable fusible metal connection, this being a well-known form of holding means; when the 55 temperature has been raised by fire conditions to a sufficient extent, the fusible metal melts and permits the two members to separate, as by gravity, by the pressure of the solutions on the closure, or by both, the cap 60 being released and permitting the solutions to be discharged.

c designates a combined commixing element and distributor, this being carried by the yoke in a position to intersect the flow 65 path of the discharging stream or streams,

thus breaking up the stream formation and causing the solutions to be commixed. If desired, the element *c* may be provided with notches *c'* through which the commixing solutions may pass, and, the notches may be arranged more or less inclined to radii of the element, and the element may be loosely mounted, in which case the notch formation may tend to set up a rotating effect on the element when the commixed solution is being discharged. If desired, the element may be provided with openings leading from the notches through the web.

As will be understood, commixing of the solutions is entirely in the open air. A small amount of commixing action may take place while the solution streams are passing from the discharge element to element *c*, but the main commixing action is provided by the action of element *c* in intersecting the streams or composite stream, breaking up the stream flow and causing the desired amount of commixture of the solutions.

Discharge element *a* may be of different types, each type, however, having independent inlets for the individual solutions, these inlets being preferably in axial alignment, although, it will be obvious, they may be arranged angularly to each other, the several inlets being arranged to permit connection to the pipes of the conduit system.

In Figs. 2 and 3 I have shown a simple arrangement in which the inlets, indicated at 10, are maintained separate by a web or partition 11 leading to the plane of the discharge opening, thus dividing the latter into discharge ports 12-12, the closure *a'* being located over these ports, a suitable sealing element 13, which may be a disk, washer, or gasket of oiled paper, being interposed between the closure and the body of element *a*. In this form, the several ports are located on opposite sides of the wall 11 which extends diametrically, as indicated in Fig. 3.

In Figs. 4 and 5, the discharge ports 12^a-12^a are shown as concentrically arranged, the division wall being in the form of a tubular member 11^a which practically forms an L with one of the inlets, the other inlet having an annular discharge port. It 115 is preferred that the areas of the two ports be approximately equal. In this form, the composite stream is made up of an annular stream of one solution with an internal stream of the other solution.

In Figs. 6 and 7, element *a* has its discharge ports arranged to provide for the discharge of the solutions in four streams, the discharge ports each being somewhat triangular in contour with the ports so connected with the inlets that alternate ports will discharge the same solution, while adjacent ports will discharge different solutions. This latter form of element *a* is preferred, since the streams are discharged in 120

such manner as to produce a quicker com-
mixture and more rapid development of the
fire extinguishing medium at the time when
rapidity of development is of the greatest
5 value.

As will be seen, each of the forms is so
arranged that while each solution is dis-
charged through a separate port, the direc-
tion of the discharge is such that the sepa-
10 rate streams are in such close relation that
they form, after discharge, practically a
composite stream, the travel of the stream
being of sufficient length to provide the com-
mixture at a point spaced from the port out-
15 lets, reducing liability of the developed mix-
ture tending to shut off discharge through
the ports, and at the same time the distance
is not of such length as would cause stream
dispersion to an extent which would carry
20 the stream out of intersection with element *c*
to any material extent. Furthermore, the
length of travel between the discharge port
and element *c* will not materially reduce the
pressure of the stream below the discharging
25 pressure of the individual streams. And
since the length of movement of each of the
discharged streams is substantially the same,
due to the particular arrangement, it will be de-
30 be understood that the solutions will be de-
livered in practically predetermined propor-
tions so as to produce a proper development
of the extinguishing medium, thereby in-
suring for maximum efficiency.

Element *c* has its active face more or less
35 concave so that the streams or composite
stream—projected under considerable pres-
sure—will be properly commixed and thrown
out in a more or less canopy-like formation
carrying the developed medium away from
40 the path of the streams being delivered.
Hence there is little likelihood of the devel-
oped medium interfering with the passage
of the solutions to the medium developing
position. Obviously, the arrangement prac-
45 tically provides for dispersion at the time
when the solutions are brought into com-
mixing relation, and the more or less violent
intermingling of the broken up streams
serves to produce a condition where the
50 chemical reactions may take place with
rapidity and, if necessary, during the move-
ment of the broken up elements through the
air in passing from element *c* to the fire.
Hence the medium is at maximum efficiency,
55 none of the ingredients having become spent
through travel in conduit or header under
conditions where chemical reaction can take
place therein.

As will be readily understood, the dis-
60 charge ports of the several forms shown are
so arranged relatively to each other that
each solution is discharged through its port
or ports in stream form, with the path of
travel of the streams adapted to place the
65 streams in juxtaposition after discharge, the

arrangement causing individual discharged
streams to form zones of a composite stream,
the juxtaposed zonal boundary portions of
the streams being formed from different so-
lutions. As a result, the general arrange-
70 ment provides for compactness, and at the
same time provides for efficient commixing
action, in that the several solutions are in
such close relation at the time when the
stream formation is broken up that the de-
75 sired chemical reaction may take place with
rapidity.

While I have herein shown and described
various ways in which the invention may be
carried into effect, it will be obvious that
variations, changes or modifications therein
may be desirable or be required in meeting
80 the needs of individual installations, and I
desire to be understood as reserving the
right to make any and all such changes or
modifications as may be found desirable
or essential, in so far as the same may fall
85 within the spirit and scope of the invention
as expressed in the accompanying claims
when broadly construed.

Having thus described my invention, what
I claim as new, is:

1. As a means for extinguishing fires by
the foam-extinguishing process, a delivery
system of the sprinkler-head type, said sys-
tem including independent lines for the sev-
eral component solutions, and a sprinkler-
head unit common to said lines, said unit
90 comprising individual discharge ports, for
the solutions, and means for maintaining
the ports closed in the absence of fire condi-
tions, said means being automatically releas-
able in the presence of fire conditions to
95 permit free discharge of the individual so-
lutions concurrently, each solution passing
100 through its discharge port in stream form
and in a direction to place the streams in
juxtaposition and in substantially commix-
ing relation after discharge.

2. As a means for extinguishing fires by
the foam-extinguishing process, a delivery
system of the sprinkler-head type, said sys-
tem including independent lines for the sev-
eral component solutions, and a sprinkler-
head unit common to said lines, said unit
115 comprising individual discharge ports for
the solutions, means for maintaining the
ports closed in the absence of fire conditions,
said means being automatically releasable in
the presence of fire conditions to permit free
120 discharge of the individual solutions con-
currently, each solution passing through its
discharge port in stream form and in a di-
rection to place the streams in juxtaposition
after discharge, and means intersecting the
125 path of travel of the discharged streams
for affecting the individual stream forma-
tions to produce commingling and commi-
xing of the components of the solutions,
whereby commixing of the solutions to pro-

duce the extinguishing medium is provided solely after solution discharge.

3. A sprinkler-head unit adapted for foam-extinguishing systems and comprising an element having independent inlets for the individual solutions and also having individual discharge ports communicating with the respective solution inlets, whereby communication between solutions will be prevented within the element, closure means for the discharge ports, and means for normally holding the closure means in port-closing position and being automatically releasable in the presence of fire conditions to permit free discharge of the individual solutions through the respective ports in stream form, the discharge ports being relatively arranged to cause individual discharged streams to form zones of a composite stream with juxtaposed zonal boundary portions formed from different solutions.

4. A sprinkler-head unit adapted for foam-extinguishing systems and comprising an element having independent inlets for the individual solutions and also having individual discharge ports communicating with the respective solution inlets, whereby communication between solutions will be prevented within the element, closure means for the discharge ports, and means for normally holding the closure means in port-closing position and being automatically releasable in the presence of fire conditions to permit free discharge of the individual solutions through the respective ports in

stream form, the discharge ports being relatively arranged to cause individual discharged streams to form zones of a composite stream with juxtaposed zonal boundary portions formed from different solutions, said unit carrying an element positioned to intersect the flow path of the composite stream and located at a point spaced from the discharge ports. 40

5. A sprinkler-head unit adapted for foam-extinguishing systems and comprising an element having independent inlets for the individual solutions and also having an internal configuration for producing individual discharge ports communicating with the respective solution inlets with the discharge ports in juxtaposed relation, said ports extending to a common plane, whereby communication between solutions will be prevented within the element, closure means for the discharge ports, and means for normally holding the closure means in port-closing position and being automatically releasable in the presence of fire conditions to permit free discharge of the individual solutions through the respective ports in stream form, said ports being relatively positioned to cause individual discharge streams to form zones of a composite stream with juxtaposed zonal boundary portions formed from different solutions. 50

In testimony whereof I have hereunto set my hand in presence of two subscribing witnesses.

DUNCAN W. PATTERSON.
